UNITED STATES PATENT OFFICE

152,102

DESIGN FOR A COMBINED BROOCH AND LOCKET

Adolph Katz, Providence, R. I., assignor to Coro,
Inc., New York, N. Y., a corporation of New
York

Application September 2, 1948, Serial No. 148,425

Term of patent 7 years

(Cl. D45—19)

To all whom it may concern:

Be it known that I, Adolph Katz, a citizen of the United States of America, residing in Providence, county of Providence, and State of Rhode Island, have invented a new, original, and ornamental Design for a Combined Brooch and Locket, of which the following is a specification, reference being had to the accompanying drawing, forming part thereof.

Fig. 1 is a plan view of a combined brooch and locket, showing my new design.

Fig. 2 is an edge view thereof.

Fig. 3 is a plan view as shown in Fig. 1, illustrating the locket portion in open position.

Fig. 4 is a rear view of Fig. 1.

I claim:

The ornamental design for a combined brooch and locket, substantially as shown.

ADOLPH KATZ.
